HARRY L. EVANS AND GEORGE I. HOHL, OF NEWPORT, RHODE ISLAND, ASSIGNEES TO
CARTONING MACHINERY CORPORATION, OF NEWPORT, RHODE ISLAND, A CORPORATION OF NEW JERSEY.

BUNDLING MACHINE.

Application filed November 14, 1927. Serial No. 233,060.

This invention relates to an improved automatic machine for bundling elongated or rod-like articles such as pencils or any other kind of trifle of stick-like form.

5 The invention has for its principal object to provide an automatic machine which is adapted to aggregate a predetermined number of articles, and then to insert said articles in an encircling band or other desired 10 form of holder; and to this end the machine of this invention is adapted to manipulate a preformed tubular casing or band, which is initially furnished in a collapsed or flat condition, whereby said casing or band is opened 15 or squared and thereafter positioned to receive the insertion therethrough of the articles to be enclosed thereby; and the machine is also designed to automatically divide from a bulk or supply of articles, such as pencils, 20 a predetermined number thereof and arrange the same in symmetrical relation preparatory to inserting the same into the opened and presented casing or band, and thereupon to complete the inserting operation whereby 25 the desired bundle of articles operated upon is obtained.

The invention has for a further object to provide means whereby the articles to be bundled may be arranged in a plurality of 30 horizontal layers, and whereby separating partitions may be inserted between the respective layers before the articles thus aggregated are inserted in the casing or band.

The invention has for a further object to 35 provide a novel arrangement and organization of mechanism whereby the several steps involved in manipulating casings or bands, aggregating the articles for insertion into said casings or bands, and if desired inserting partition members between layers of the aggregated articles, are coordinated and relatively timed for operation so that the casings and bands will successively and speedily pass through the machine and receive their 40 respective quotas of articles to be bundled thereby, all in a manner whereby the various operations are automatically carried on in timed relation and so as to rapidly produce and deliver the articles in desired bundled 45 form.

Other objects of this invention, not at this time more particularly enumerated, will be

clearly understood from the following detailed description of the same.

The invention is clearly illustrated in the 55 accompanying drawings, in which:

Figure 1 is a plan view of the novel bundling machine made according to and embodying the principles of this invention; Figure 2 is a fragmentary longitudinal section taken on line 2—2 in Figure 1 but drawn on an enlarged scale; Figure 3 is a rear side elevation of the machine with certain parts of the hopper and article feeding mechanism shown in section; Figure 4 is a detail transverse section taken on line 4—4 in Figure 1; Figure 5 is a detail section on line 5—5 in Figure 1 but drawn on an enlarged scale; Figure 6 is a detail section taken on line 6—6 in Figure 1, being also drawn on an enlarged scale.

Similar characters of reference are employed in all of the hereinabove described views, to indicate corresponding parts.

The machine of this invention is adapted 75 to manipulate a form of casing or band comprising a rectangular hollow tubular body 1 having open opposite ends, said body being so scored longitudinally, between the sections making up the sides of the same, that it may 80 be initially collapsed into a relatively flat condition as shown in Figures 1 and 2. The casing or band in this form is preferably made of light weight cardboard and is furnished by the manufacturer thereof to the user in the 85 aforesaid collapsed or flat form. The operation of raising the casing or band 1 from such initial flat or collapsed condition to a properly set up or open condition may be referred to as "squaring" the casing. The machine, 90 which is the subject of the present invention, is adapted to receive the flat or collapsed casings or bands 1, stacked one upon another, into a suitable holder or magazine, from which the same are successively ejected to 95 thereupon undergo the squaring whereby the same are opened and thereafter positioned to receive the articles to be inserted therein.

The reference character 2 indicates a suitably supported base plate or bed, upon which 100 is supported, by standards 3, a deck plate or platform 4, which is spaced above said bed in horizontal relation thereto, but which is longitudinally offset toward the left end of

said base plate or bed. Mounted in bearings 5 in transverse extension over the right hand end of the base plate or bed 2 is a power transmission shaft 6. The shaft 6 is started, driven, and stopped by means of a clutch mechanism 7, with which the same is provided. Said clutch mechanism 7 is operated through suitable transmission means, such as drive chain 8, from any suitable source of power, such e. g. as an electric motor (not shown). Also mounted in bearings 9, for extension over and adjacent to the rear longitudinal side of said base plate or bed 2, is an auxiliary transmission shaft 10; this shaft 10 being driven from said shaft 6 through intermeshing bevel gears 11.

The casing or band delivery and squaring mechanism.

20 Supported upon the right hand end of said platform 4 is a magazine or stacker 12 which is adapted to contain a supply of the initially flat or collapsed casings or bands desired to be passed through the machine. Means are provided for successively ejecting the collapsed casings or bands from said magazine or stacker 12, and delivering the same to the squaring mechanism; said means comprises a slide block 13, which is mounted for longitudinal reciprocation in guides 14, and which is provided with a plunger 15 suitably affixed thereto. Said plunger 15 is provided rearward of its forward end with a transverse shoulder 16 of a height not exceeding the thickness of a single collapsed casing or band. The forward movement of the plunger 15 carries said shoulder 16 into engagement with the rearward edge of the bottommost collapsed carton of the pile thereof contained in the magazine or stacker 12, so that as the plunger is moved forward said bottom casing or band is engaged and pushed outwardly from the magazine or stacker 12. The means for producing a properly timed reciprocation of the ejecting plunger 15 comprises a fulcrum member 17 secured upon the base plate or bed 2 with which is pivotally connected a lever 18, the upper end of which is connected through a link 19 with the slide block 13. 40 Actuated by the transmission shaft 6 is an eccentric 20, the connecting rod or arm 21 of which is pivotally attached to the lever 18 intermediate its ends, all whereby, as the eccentric is rotated, a forward and back oscillation of the lever arm will be produced effective to in turn produce the desired forward and back reciprocation of the slide block 13 and ejecting plunger 15.

Disposed beneath the magazine or stacker 12 and extending longitudinally forward therefrom in spaced relation above the deck-plate or platform 4 are a plurality of radially spaced supporting bars 22 upon which the casings or bands are supported and over which they move as they proceed through the

machine. The forward limit of movement of the ejecting plunger 15 positions a casing or band upon the supporting bars 22 and in front of a clamp plate mechanism. Mounted for horizontal reciprocating movement in a guide block 23, which is fixed upon the platform 4, is a substantially flat clamp blade 24, with which is aligned the ejected casing or band. The means for producing a properly timed reciprocation of said clamp blade 24 comprises a race cam 25 rotated by the transmission shaft 10 and operative through a connecting rod 26 to oscillate a lever 27, the free end of which is connected by a link 28 with the tail end 29 of said clamp blade. The operation of the race cam 25 is such that a properly timed forward movement of the clamp blade 24 is produced, whereby the same is caused to insert itself between the collapsed walls and upon the bottom wall of the ejected casing or band, to thereby firmly and non-shiftably retain the latter in its initial ejected position subject to the action of squaring mechanism to be presently described. In order to prevent endwise displacement of the ejected casing or band while the clamp blade is entering the same, a suitable stop means 30 is provided to abut that end of the ejected casing or band opposite to which the clamp blade enters, this stop means comprising a depending plate supported by an arm 31 affixed to one side of the magazine or stacker 12, or the same may comprise any other suitable form of stop means otherwise supported.

The means for opening up or squaring the ejected casing or band, while the same is held against displacement by the clamp blade 24, comprises a vertically reciprocable squaring member 32 the lower end of which is slidably in a guide member 33. The upper end of said squaring member is formed to provide upstanding forward fingers 34 and spaced rearwardly therefrom, for a distance corresponding to the width of the opened or squared casing or band, upstanding rearward fingers 35 provided with invariably chamfered free ends 36. The fingers 34 are of slightly greater height than the fingers 35. Initially, as a casing or band is being ejected from the magazine or stacker 12, the squaring member 32 occupies a lowered position intermediate its fully lowered and its fully raised positions, so that the free ends of the fingers 34 are projected slightly above the level of the supporting bars 22, while the free ends of the fingers 35 are below such level. In this position, as the ejected collapsed casing or band is moved out of the magazine or stacker, the forward edge of the same is stopped against the slightly upwardly projecting ends of the fingers 34, thus properly disposing the same for the reception of the clamp blade 24. After the clamp blade has been inserted, the squaring member is caused to rise and as it rises the fingers 34 and 35

are carried above the supporting bars 22 with the effect that the chamfered ends of the fingers 35 engage an underlying side wall of the collapsed casing or band so as to turn 5 the same upward, thus raising the sides and upper portions of the casing or band causing such parts to turn about the score lines intermediate the same, thus opening the casing into the "squared" or tubular form ready 10 for the reception of the articles to be inserted therein, as will be understood from an inspection of Figure 2 of the drawings.

The means for producing the properly timed vertical reciprocatory motions of the 15 squaring member 32 comprises a race cam 45 actuated by the transmission shaft 10 and in turn actuating a bell crank mechanism, the one arm 46 of which is pivoted to connecting rod 47 which is actuated by the race cam 45, 20 and the other arm 48 of which cooperates with a stud 49 extending from the lower end of the squaring member 32 whereby oscillations of the bell crank means are converted into properly timed vertical reciprocations of said 25 squaring member.

In order to hold the squared casing or band against longitudinal displacement as the clamp blade is withdrawn therefrom after the squaring operation, a stop means is provided 30 comprising a lever arm 37 pivotally supported by fulcrum blocks or ears 38 mounted on top of the guide block 23, so that said lever arm extends toward the adjacent end of the casing or band. Said lever arm is normally 35 depressed in position to engage a casing or band by means of a compression spring 39 which is backed by a stationary bracket or abutment 40 connected with said guide block 23. In order to so dispose the lever arm 37

40 as not to interfere with the squaring operation exercised upon the casing or band, means are provided in the form of a cam 41 carried on the top of the clamp blade 24 and cooperating with a nosing 42 on the underside of the 45 lever arm 37 whereby when the clamp blade is entered in the casing or band said cam 41 is positioned to raise the lever arm 37 against the compression of the spring 39. As the clamp blade is retracted, however, said cam 50 portion 41 is removed from engagement with the nosing 42 and the tension of the spring 39 depresses the lever arm 37 to lower its free end whereby a transverse lip 42 provided at the upper outer end of said arm is caused to 55 engage with and over the marginal end portions of the said arm registers against the adjacent end of the casing or band, thus firmly holding the latter against displacement by the retractive movement of the clamp blade.

60 After the casing or band has been squared means are provided to move the same upon the supporting bars 22 to a position ready for the reception of the articles to be inserted therein. The means for so moving the 65 squared casings or bands is arranged to effect

step by step or intermittent movements whereby a stationary dwell of the same is provided for at desired location, of sufficient duration to permit the insertion of articles therein.

70

A conveyor or transfer mechanism suitable for intermittently moving the casings or band comprises a longitudinally reciprocable carrier block 50, movable in suitable slideways 51 fixed on the underside of the platform 4. The 75 means for reciprocating said carrier block 50 comprises a race cam 52 from which extends a connecting rod 53, the free end of which is pivotally connected with an oscillatable lever 54 fulcrumed on a pivoting support 55 80 mounted on the base plate or bed 2. The said carrier block 50 is interconnected with the free end of said lever 54 by means of a link 56, whereby oscillations of said lever arm 54 will produce the desired forward and back- 85 ward reciprocatory movements of said carrier block 50. Connected with said carrier block 50 so as to travel therewith, but being so arranged as to be capable of independent vertical reciprocation relative to said carrier 90 block, are the body portions 57 of a pair of laterally spaced conveyor or transfer members 58 which are adapted to move in the spaces between certain of the supporting bars 22. Said conveyor or transfer members are 95 provided with upstanding fingers 59 so adjacent end of the casing or band, thus firmly ranged as to engage or embrace the squared cartons when said conveyor or transfer members 58 are moved upwardly toward the latter. 100 The platform 4 is also provided with longitudinal openings 60 to permit both the longitudinal and vertical reciprocations of said conveyor or transfer members.

The means for producing the vertical reciprocations of the conveyor or transfer members, 58, whereby the same are caused to move in an elevated plane with their fingers 59 projecting above the supporting bars 22 into propelling engagement with the casings or bands 105 1 to move the latter forwardly, and in a lowered plane with their fingers 59 withdrawn beneath the casings or bands when the conveyor or transfer members are retracted after a forwardly propelling stroke, comprises the following mechanisms: Fulcrumed upon parts 61, mounted on said base plate or bed 2, are bell-crank devices 62. Pivotally connected with the substantially horizontal members of said bell-crank devices, so as to 110 extend longitudinally and horizontally therebetween, and so as to be supported thereby, is a vertically oscillatable guide cradle 63 which provides a guideway 64 for a roller 64' journaled to extend between the lower extremities 115 of the body portions 57 of said conveyor or transfer members 59, to thereby support the latter and control the raised and lowered positions of the same as governed by the timed rise and fall of said guide cradle 63. The 120 125 130

properly timed rise and fall of said guide cradle 63 is produced by the oscillation of said bell-crank devices 62, which move harmoniously, since the substantially vertical members thereof are connected together by a link 65. Timed oscillatory movements are imparted to said bell-crank devices 62, through the operation of a race cam 66 which is fixed on said transmission shaft 6, and which actuates a connecting rod 67 the free end of which is pivotally connected with a vertical member of one of said bell-crank devices 62.

Extending from the magazine or stacker 12 parallel to and spaced above the supporting bars 22 for a distance equivalent to the height of a set up or squared casing or band 1 is a keeper bar 68, which is pivotally connected at its rearward end with a supporting bracket 69 connected with said magazine or stacker 12, 20 and which is supported to its outer end by a holding member 70, in such manner that the same may be raised to give access to the underlying casings of bands if desired.

In the operation of the machine, after the squaring member 32 has risen to square a casing or band which has been delivered from the magazine or stacker 12, the conveyor or transfer mechanism is timed to withdraw the conveyor or transfer member 58 to its lower level of movement, whereupon the same is retracted to bring the rearmost set of embracing fingers 59 beneath the casing or band which has been squared by rise of the squaring member 32, whereupon the conveyor or transfer member is caused to rise so that said latter fingers will embrace the casing or carton which has been set up or squared and as this occurs the squaring member 32 is downwardly withdrawn to its full extent to free the set up carton from the fingers 34 and 35 thereof. Upon withdrawal of the squaring member 32 and its fingers 34 and 35, the conveyor or transfer member 58 is timed, under the operation of its actuating mechanism, to move forward, thus imparting to the set up and squared casing or band a forwardly propelling movement which carries the same from the position A indicated in Figure 2 to the position B indicated in said Figure 2. 50 A casing or band which has previously been set up or squared and delivered to the station B is at the same time embraced by the intermediate set of fingers 59 and is moved from said station B to station C, which latter station is aligned with the article aggregating and inserting mechanism and which constitutes what may be termed the filling station. At the same time a casing or band which had previously occupied the filling station C is 60 engaged by the remaining finger 59 and is removed away from said station, all of which will be readily understood from an inspection of Figure 2 of the drawings.

In order to retain the casings or bands against lateral displacement, after the same

are delivered to either the station B or C and when disengaged by the conveyor or transfer means, yieldable detent means are provided in connection with one of said supporting bars 22 and with said keeper bar 68. The detent means connected with the supporting bar 22 comprises a flat spring 71 secured by one end in an anchoring means 72 and having its opposite or free end slidably supported in a slide member 73. Said anchoring means 72 and slide member 73 are affixed to the underside of a supporting bar 22 so that said spring 71 extends beneath and parallel to said supporting bar 22. Secured to said spring adjacent to each station B and C is a transverse yoke device 74 provided at each end thereof with upstanding detent fingers 75 disposed one on each side of the supporting bar 22. Said detent fingers 75 are rounded off or chamfered at their rearward sides and normally engage the forward sides of the casings or bands occupying the said stations B and C. In like manner, there is mounted by means of an anchoring member 76, so as to extend above the keeper bar 68, a flat spring 77 and adjacent to the rearward free end of said spring 77 is a stop means 78. Secured upon said spring member 77 adjacent to each station B or C are transverse yoke members 79 having at their ends depending detent fingers 80, the rearward sides of which are beveled or chamfered as shown. These detent fingers 80 are so disposed as to engage the rearward sides of casings or bands, which have been moved to the stations B and C. In 100 operation, as the conveyor or transfer member 58 propels a set up or squared casing or band from the squaring station A to the intermediate station B and a casing or band from the station B to the filling station C, the 105 detent fingers 80, when their beveled free ends are engaged by the forwardly moving casings or bands, will yield upwardly against the tension of the spring 77, so that said casings or bands may pass under said detent fingers 110 into the respective stationed positions B and C, whereupon the detent fingers will be pressed downwardly by the spring 77 to occupy a retaining relation to the upper rearward corner portions of the said casing or 115 bands, while the lower forward corner portions of the latter are engaged by the upwardly projected detent fingers 80. As the conveyor or transfer member moves a casing or band from the respective stations B and C the detent fingers 80 will be depressed against the tension of the spring 71 so that the said casings or bands will ride over said detent fingers 80. It will thus be obvious that the detent fingers 75 and the detent fingers 80 engaging opposite sides of the casings or bands respectively at the upper and lower 120 portions of said sides will tend to hold the empty casings or bands against collapse and in their proper set up or squared condition 130

ready for the reception of the articles to be inserted therein, and yet the detent means thus provided will readily yield to the onward movement of the casings or bands under the 5 impulsion of the conveyor or transfer means.

The article aggregating and inserting mechanism.

Arranged laterally adjacent to filling station C is the means for assembling or aggregating articles from bulk into a group of desired number, and then inserting the group thereof into a casing or band. In the illustration of this invention disclosed in the 10 drawings, the articles operated upon are lead pencils, although it will be obvious that any other specific kind of article of elongated or stick-like form may be manipulated by the machine.

20 Fixed by their inner ends to the deck-plate or platform 4 are a pair of spaced apart channeled guide bars 81 to extend transversely and outwardly therefrom. Fixed by its inner end to said base plate or bed 2, to extend transversely and outwardly therefrom and beneath said guide bars, is a bracket plate 82. Interconnecting the outer end of said guide bars and bracket plate are uprights 83 to provide a rigid construction. 25 Mounted in and between said guide bars 81 to reciprocate therein is a slide-block 84 upon which is fixed for movement therewith a plunger block 85 constructed to provide a primary plunger member 86, and formed at its forward end to provide a secondary plunger member 87 stepped down in plane and extending forwardly from the operative end of said primary plunger member 86. Formed by side plates 88 suitably supported 30 by frame-pieces 89 to extend along the opposite sides of and above said primary plunger 86 is an assembling box 90 having end closing means 91 at the portion thereof projecting above said primary plunger. Extending longitudinally through the interior of said 35 assembling box 90 in laterally spaced apart relation receiving spaces within which the articles, such as the pencils 93, may be disposed in vertical tiers. Preferably the upper face of said primary plunger member 86 is longitudinally grooved, so that the lower marginal portions of said partitions 92 may be engaged therein. Connected with the 40 sides of said assembling box are angle plates 94, the upper lateral extensions 95 of which project outwardly from opposite sides of and in the plane of the upper open side of said assembling box, thereby forming a stationary support for the pencils disposed in bulk 45 in a hopper 96 which is mounted above said assembling box, and which is adapted to deliver the pencils as needed into the latter. In order to agitate the pencils contained in the 50 hopper and to so roll or move the same laterally back and forth across the mouth of said 55

assembling box as to assure the filling of all the vertical receiving spaces provided by the partition members thereof, said hopper is provided with a bottom opening and downwardly sloping bottom walls 97 extending 60 from its ends to each side of said bottom opening, and said hopper is mounted for lateral oscillation. To arrange the hopper to permit of the desired lateral oscillation thereof, supporting arms 98 are pivotally 65 mounted on the deck-plate or platform 4 in spaced apart parallel relation, and with their upper ends in turn pivotally connected with laterally spaced apart points on the under side of the respective bottom walls 97 70 of said hopper. The means for producing the oscillation of said hopper comprises a yoke arm 99 extending downwardly from the fulcrum point of one of said supporting arms 98. Rotatably journaled in a suitable bearing means, which may be in part formed in connection with the standard 3, is a transverse shaft 100 upon which is fixed an eccentric cam 101, adapted to be operatively engaged or embraced by said yoke arm 99. Said shaft 100 and cam 101 are driven from 75 said transmissions shaft 10 by intermeshing bevel gears 102. In order to assure the desired rolling movement of the pencils 93 toward the opposite sides of the assembling 80 box as the bottom opening of the hopper is moved back and forth over the stationary supports 95, I provide upon the latter a plurality of inclined ribs 103 descending toward the sides of the assembling box, so that the 85 pencils will easily roll from one side or the other over the mouth of said assembling box. The hopper bottom walls 97 bordering the supports 95 are notched out to conform to the ribs 103, as is shown in Fig. 4 of the 90 drawings.

The plunger block 85, during the operation of the machine, is reciprocated longitudinally beneath said assembling box in which the pencils 93 disposed in a predetermined number 95 of tiers; in the instant case there are four tiers of pencils, and the primary plunger member is designed to discharge from the assembling box, at each operation, three layers or groups of three pencils from each tier thus 100 assembling one dozen pencils to make up each ultimate bundle thereof produced by the machine operations. The means for producing the timed reciprocations of the plunger block 85 comprises a race cam 104 mounted on and 105 rotated by said transmission shaft 10. Pivotally in bearings 105 fixed on the outer end portion of said bracket plate 82 is the fulcrum spindle 106 of an oscillatable lever 107, the upper free end of which is operatively interconnected by link 108 with said slide block 84, and said lever 107 is oscillated by means of a crank-arm 109 with which is connected the free end of a connecting rod 110 adapted 110 to be actuated by said race cam 104, all of 115 120 125 130

which will be understood from an inspection of Fig. 4 of the drawings more particularly. In the operation of the plunger block 85, the pencils 93 within the assembling box initially 5 rest upon the upper surface of said plunger block 85. As said plunger block 85 is retracted to its rearmost position, its supporting surface will be withdrawn, so that the assembled pencils will drop down through the 10 bottom of the box upon the upper surface of the secondary plunger member 87 and in front of the primary plunger end 86 of said plunger block. The height of the primary plunger end 86 is predetermined in the instant case to equal the height of three layers 15 of pencils, and consequently as the plunger block moves forward three horizontal layers of pencils, each layer comprising four pencils, will be impelled end wise away from the assembling box by the forward thrust of the primary plunger end 86, the thus segregated and assembled group of one dozen pencils being supported during such initial movement upon the upper surface of said secondary plunger member 87. The group of pencils thus discharged from the assembling box, are carried by the forward thrust of the plunger mechanism outwardly between a pair of retaining side walls 111 which bound a passageway 112 in and through which the secondary plunger member 87 may be moved, and which serves to retain the pencils in the desired grouped relation. Arranged at the rearward end of said passageway 112 is a 25 vertically disposed frame 113 in which is mounted for vertical reciprocation a movable gate member 114. This gate member 114 is actuated, in properly timed relation to the reciprocatory movements of said secondary plunger member 87, by a pivoted rock-lever 115, one end of which is pivotally connected with the gate member 114, and the other end of which is connected by a link 116 to a pivoted actuating lever 117, the outer 30 end of which coacts with a peripheral cam 117', connected with the circumference of the race cam 45 (see Figs. 1, 3 and 4). The operation of the gate-member 114 is so timed that, when the plunger member 86 and secondary plunger member 87 move forward, with the group of pencils impelled by the former while carried on the latter, the gate-member 114 is held in raised position so that the group of pencils may pass with the plunger member 87 beneath the same and into the passageway 112. A transverse stop means 118 positioned adjacent to the outer limit of the stroke of said plunger member 87 and at the outer end of the passageway 112, and above the level of the top surface of said plunger member 87 serves to retain the group of pencils from forward longitudinal displacement while supported by said plunger member 87. Prior to the retraction of the 45 plunger member 87, the gate member 114 is

operated by its actuating means to drop behind the group of pencils entered in the passageway 112, so that as the said plunger member 87 is retracted the pencils will be retained within said passageway. When the plunger 50 member 87 is retracted, the group of pencils will drop down to the lower level of the passageway 112, and upon a floor-plate 119 situated in the plane of the supporting bars 22. In order to retain the group of pencils against 55 vertical displacement or disturbances of their desired grouped relation, there is provided a keeper-plate 120, adapted to move downward with the pencils when, upon withdrawal of the plunger member 87, the same are lowered 60 to and upon the floor-plate 119. To provide for properly timed actuation of said keeper-plate 120, to raise the same prior to entrance of the pencils within the upper level of said passageway 112 and to lower the same upon 65 withdrawal of said plunger member 87, a pivoted beam 121 is fulcrumed on a pivot post 122, with its outer end provided with a roller or stud 123 engaged in the race groove of a race cam 124 rotated by the shaft 10 to 70 produce properly timed oscillations of said beam 125 is coupled at one end by an interconnecting link 126 with the free end of the actuating beam 121, and has its opposite end pivotally connected with the keeper-plate 120 75 (see Figs. 1, 3 and 4).

While the group of pencils rests on the floor-plate 119 and before they are finally propelled outwardly from the passageway 112 and into the awaiting casing or band 1, means are provided for inserting between the horizontal layers of pencils for making up the group thereof separating partition devices 127, usually comprising rectangular pieces of cardboard or other suitable material, said means comprising the following mechanism.

Suitably supported above the deck-plate or platform 4, at the respective sides of the passageway 112, are shelf members 128 and 129, one of the same, as 128, having its top surface aligned with a plane intermediate the top and middle layers of the group of pencils, and the other, as 129, having its top surface aligned with a plane intermediate the middle and bottom layers of the group of pencils, when said pencils rest upon the floor-plate 119 and within the passageway 112. Respectively supported upon said shelf members 128 and 129 are upstanding magazines or stackers 130 to contain supplies separating partition devices 127. Extending between each magazine or stacker 130 and the passageway 112 and respectively spaced above and parallel to the shelf members 128 and 129 are top-plates 131 which define ways 132 leading from the bottom of the magazines or stackers into communication with the sides of the passageway 112 to give access to the group of pencils within the latter. 130

Slidably reciprocable on each shelf-member 128 and 129 and beneath each magazine or stacker 130 are push-plates 133, each of which is provided in rearwardly spaced relation to their free end with a partition device receiving seat having at its rear end a shoulder 134 to initially engage and remove from the adjacent magazine or stacker the lowermost partition device of the pile contained in the latter. The means for producing timed reciprocation of said push plates 133 toward and away from the passageway 112 and the group of pencils therein, vertically spaced apart and opposed racks 135 slidably supported in corresponding slide-ways 136. A rotatable pinion 137 is mounted in fixed location to internmesh at opposite sides thereof with said racks 135. One push-plate is connected by a coupling block 138 with the rear end of one rack, and the other push-plate is connected by a coupling block 139 with the rear end of the other rack, all in such manner that reciprocatory movement of one rack to actuate one push-plate 25 toward and away from one side of the passageway 112 will, through the rotation imparted to the pinion 137 produce a reciprocatory movement of the other rack to simultaneously actuate the other push-plate 30 toward and away from the opposite side of the passageway 112, the respective shelf-member 128 and 129 having openings or ways 128' and 129' to accommodate the movements of said coupling blocks 138 and 139 respectively, all as will be obvious from an inspection of Fig. 5 of the drawings. The means for producing properly timed reciprocations of the racks and the push-plates actuated thereby, consists in an eccentric 40 mounted on and actuated by the transverse shaft 100, the connecting-rod 141 of which is pivotally attached to a coupling lug 142 connected with the lowermost rack, which lug extends through and rides in an opening 45 143 provided in the deck-plate or platform 4.

After the group of pencils has been deposited in the passageway 112, and while temporarily detained therein during the retraction of the plunger members 86—87, the push-plates 133 are caused to move forward to propel toward the group of pencils and then intermediate the layers thereof partition devices 127 which have been previously deposited on the respective shelf-members 55 128 and 129 in front of the push-plate extremities. At the same time such partition devices are being inserted between the layers of pencils forming the group of the latter deposited in the passageway 112, the forward movement of each push-plate engages by means of the shoulders 134 the bottom partition device of each stack thereof and carries the same in supported relation on the push-plates seats out of the respective magazines or stackers. Pivotaly mounted gravity actuated check-pawls 144 having chamfered downwardly directed fingers 145 ride on the surface of each push-plate. These check-pawls 144 yield to the outward movement of the partition devices carried outwardly in the seats of the push-plates, so as to ride over the same in such manner as to fall or drop behind the rear edges thereof when the push-plates reach the outer limits 75 of their forward strokes, and consequently, when said push-plates are retracted the partition devices are prevented from traveling back therewith, being held by the check-pawls while the push-plates are withdrawn 80 and being thus deposited on the shelf member in front of the free extremities of push-plates ready to be propelled forward by the latter and inserted between the layers of a group of pencils subsequently deposited in 85 the passageway 112. These operations will be fully understood from an inspection of Fig. 5 of the drawings more particularly.

After the partition devices 127 have been inserted between the layers of pencils making 90 up a group thereof deposited in the passageway 112, said group is ready to be finally ejected from the passageway 112 and inserted in the waiting casing or band 1. The final insertion of the pencils into the casing or 95 band is effected as follows. The primary plunger 86 and secondary plunger 87 having been retracted to pick up from the delivery and segregating means a following group of pencils to be carried into the passageway 112 100 upon the top of the secondary plunger 87 and under the thrust of the primary plunger 86, the free end of said secondary plunger 87 will on the next forward movement thereof engage the group of pencils previously deposited in the passageway 112 and on the platform 119 and will thrust the same outwardly and into the awaiting casing or band 1 which is supported in alignment with the plunger at the station C in the manner clearly 110 to be understood, thus completing the bundling operation. The casing or band 1 at the station C is retained against longitudinal displacement under the thrust of the pencils by means of a stationary stop post 146 (see 115 Fig. 1).

After each group of pencils is bundled and encased in the casing or band, the same is removed from the station C by the push fingers 59 of the conveyor or transfer members 120 58, and at the same time a succeeding empty casing or band is deposited at station C. The completed bundles of pencils are successively pushed along in a train on the supporting bars 22 as they leave the filling station C, from 125 whence they may be removed from the machine ready for boxing, packing or other handling.

From the above description of the construction, arrangement and operation of the various mechanisms making up the bundling machine of this invention, the functioning of the machine as a whole will be clearly understood without necessity for further recapitulation except to say that the operations are carried out in a continuous manner, the various mechanisms being synchronized for proper correlation as will be clearly evident.

It will be obvious that many changes may be made in the various arrangements and combinations of the several cooperating mechanisms, as well as in the details of the construction of the same, without departing from the scope of this invention as defined in the appended claims. Hence, we do not limit our invention to the exact arrangements and combinations as described in the foregoing specifications, nor do we confine ourselves to the exact details of the construction of the mechanisms and parts thereof as shown in the accompanying drawings, and such description and showing are to be taken as illustrative and not in a limiting sense.

We claim:—

1. A machine for bundling stick-like articles, comprising a hopper to contain a bulk of said articles, an assembling box beneath and fed by said hopper having means to aggregate articles to form bundles with the articles disposed in symmetrical layers, means to oscillate said hopper over said assembling box to cause said articles to pass from the former into the latter, means to segregate and initially advance bundles from said assembling box, means to supply tubular casings open for the reception of said advanced bundles and into axial alignment therewith, and means to finally thrust said advanced bundles endwise and into said casings.

2. A machine for bundling stick-like articles, comprising a hopper to contain a bulk of said articles, an assembling box beneath and fed by said hopper having means to aggregate articles to form bundles with the articles disposed in symmetrical layers, means to oscillate said hopper over said assembling box to cause said articles to pass from the former into the latter, means to segregate and initially advance bundles from said assembling box, means to supply collapsed casings, means to open said casings into tubular form, means to present said casings endwise to said advanced bundles, and means to finally thrust said advanced bundles endwise into said casings.

3. A machine for bundling stick-like articles, comprising means to assemble from bulk predetermined numbers of articles into bundles, means to supply tubular casings open for the reception of said bundles and in endwise alignment therewith, means to insert said bundles endwise into said casings, and

means to supply and directly insert separating members between layers of articles forming said bundles prior to insertion of the latter into said casings.

4. A machine for bundling stick-like articles, comprising a hopper to contain a bulk of said articles, an assembling box beneath and fed by said hopper having means to aggregate articles to form bundles thereof with the articles disposed in symmetrical layers, means to supply tubular casings open for the reception of said bundles, means cooperating with said assembling box to transfer said bundles therefrom and endwise into said casings, and means to directly insert separator elements between the layers of articles of each bundle prior to transfer thereof into a casing.

5. A machine for bundling stick-like articles, comprising a hopper to contain a bulk of said articles, an assembling box beneath and fed by said hopper having means to aggregate articles to form bundles thereof with the articles disposed in symmetrical layers, means to oscillate said hopper over said assembling box to cause said articles to pass from the former into the latter, means to segregate and initially advance bundles from said assembling box, means to supply collapsed casings, means to open said casings into tubular form, means to present said casings in axial alignment with advanced bundles for the reception thereof, means to transfer said advanced bundles therefrom and endwise into said casings, and means to directly insert separator elements laterally between the layers of articles of each bundle prior to transfer thereof into a casing.

6. A machine for bundling stick-like articles, comprising means to supply collapsed casings, means to open said casings into tubular form, guideway means for said opened casings, means to progressively move opened casings crosswise through said guideway, yieldable means connected with said guideway to engage the sides of and thus retain said casings in open condition prior to filling of the same, means laterally off-set relative to said guideways to assemble from bulk predetermined numbers of articles into bundles, and means to insert said bundles endwise into said open casings while the latter are supported in said guideway.

7. A machine for bundling stick-like articles, comprising means to supply collapsed casings, means to open said casings into tubular form, guideway means for said opened casings, means to progressively move opened casings crosswise through said guideway, yieldable means connected with said guideway to engage the sides of and thus retain said casings in open condition prior to filling of the same, a hopper to contain a bulk of articles, means fed by said hopper and laterally off-set relative to said guideways to ag-

gregate articles to form bundles thereof, and means to insert said bundles into said open casings while the latter are supported in said guideway.

5 8. A machine for bundling stick-like articles, comprising means to supply collapsed casings, means to open said casings into tubular form, guideway means for said opened casings, means to progressively move opened casings crosswise through said guideway, yieldable means connected with said guideway to engage the sides of and thus retain said casings in open condition prior to filling of the same, a hopper to contain a bulk of 10 said articles, an assembling box beneath and fed by said hopper having means to aggregate articles to form bundles with the articles disposed in symmetrical layers, and means cooperating with said assembling box to 15 transfer said bundles therefrom and endwise into said open casings while the latter are in said guideway.

9. A machine for bundling stick-like articles, comprising means to supply collapsed casings, means to open said casings into tubular form, guideway means for said opened casings, said casings being disposed transversely of said guideway to move sidewise therein, means to progressively move opened 20 casings through said guideway, yieldable means connected with said guideway to engage the sides of and thus retain said casings in open condition prior to filling of the same, a hopper to contain a bulk of said articles, an 25 assembling box beneath and fed by said hopper having means to aggregate articles to form bundles with the articles disposed in symmetrical layers, said hopper and assembling box being laterally off-set relative to 30 said guideway, a reciprocable plunger means 35 cooperating with said assembling box to transfer bundles therefrom and to insert said bundles endwise into said casings while the latter are retained in open position in said 40 guideway.

45 10. In a machine for bundling stick-like articles, a supporting means in horizontal plane, means to supply collapsed tubular casings at one end of said supporting means, means to open said casings, means to intermittently and progressively move the open casings successively over said supporting means, a keeper bar spaced above and parallel to said supporting means, spring-pressed 50 fingers connected with both said supporting means and said keeper-bar to engage diagonally opposite corners of said open casings to retain the same against collapse while at rest, means to assemble from bulk predetermined 55 numbers of articles into bundles, and means aligned with a point of rest of said casings adapted to transfer said bundles from said assembling means and into the casings.

60 11. In a machine for bundling stick-like articles, a supporting means in horizontal

plane, means to supply collapsed tubular casings at one end of said supporting means, means to open said casings, means to intermittently and progressively move the open casings successively over said supporting 70 means, a keeper bar spaced above and parallel to said supporting means, spring-pressed fingers connected with both said supporting means and said keeper-bar to engage diagonally opposite corners of said open casings to retain the same against collapse while at rest, a hopper to contain a bulk of said articles, an assembling box beneath and fed by 75 said hopper having means to aggregate articles to form bundles in which the articles are disposed in symmetrical layers, and a reciprocable plunger means cooperating with said assembling box and aligned with a point of rest of said casings operative to insert bundles into said casings.

80 12. A machine as defined in claim 9, including means to directly insert separator elements laterally between the layers of articles in each bundle thereof prior to insertion of said bundles into said casings.

85 13. A machine as defined in claim 11, including means to directly insert separator elements laterally between the layers of articles in each bundle thereof prior to insertion of said bundles into said casings.

90 14. In a machine of the kind described, an assembling box partitioned lengthwise and open top and bottom, said assembling box being adapted to dispose articles in symmetrical layers one above the other, a hopper to 100 contain a bulk of articles, said hopper having inclined bottom portions converging on a bottom opening beneath which said assembling box is disposed, means to oscillate said hopper to cause articles to pass therefrom into the partitioned interior of said assembling box, a plunger means stepped to provide a primary plunger adapted to eject a predetermined number of articles from said assembling box to form bundles each comprising a plurality of layers and a secondary plunger extending forwardly therefrom, said plunger means being disposed to reciprocate beneath the open bottom of said assembling box, a platform beneath said plunger means, means to provide a passageway above said platform and aligned with said plunger means, and into which formed bundles are transferred by said primary plunger, and means to successively position open casings 110 in alignment with said passageway to receive bundles of articles ejected from the latter by said secondary plunger.

115 15. In a machine of the kind described, an assembling box partitioned lengthwise and open top and bottom, said assembling box being adapted to dispose articles in symmetrical layers one above the other, a hopper to 125 contain a bulk of articles, said hopper having inclined bottom portions converging on a bot-

- tom opening beneath which said assembling box is disposed, means to oscillate said hopper to cause articles to pass therefrom into the partitioned interior of said assembling box,
- 5 a plunger means stepped to provide a primary plunger adapted to eject a predetermined number of articles from said assembling box to form bundles each comprising a plurality of layers and a secondary plunger
- 10 extending forwardly therefrom, said plunger means being disposed to reciprocate beneath the open bottom of said assembling box, a platform beneath said plunger means, means to provide a passageway above said platform and aligned with said plunger means and into which formed bundles are transferred by said primary plunger, means timed in relation to the reciprocation of said plunger means to retain bundles in said 45 passageway while said plunger means is retracted, means to supply and insert separator elements between the layers of articles while the bundles thereof are at rest in said passageway, and means to successively position 50 open casings in alignment with said passageway to receive bundles of articles ejected from the latter by said secondary plunger.
- 15 16. In a machine of the kind described, an assembling box partitioned lengthwise and open top and bottom, said assembling box being adapted to dispose articles in symmetrical layers one above the other, a hopper to contain a bulk of articles, said hopper having inclined bottom portions converging on a bottom opening beneath which said assembling box is disposed, means to oscillate said hopper to cause articles to pass therefrom into the partitioned interior of said assembling box, a plunger means stepped to provide a primary plunger adapted to eject
- 55 a predetermined number of articles from said assembling box to form bundles each comprising a plurality of layers and a secondary 40 plunger extending forwardly therefrom, said plunger means being disposed to reciprocate beneath the open bottom of said assembling box, a platform beneath said plunger means, means to provide a passageway above said 45 platform and aligned with said plunger means and into which formed bundles are transferred by said primary plunger, means timed in relation to the reciprocation of said plunger means to retain bundles in said 50 passageway while said plunger means is retracted, means to supply and insert separator elements between the layers of articles while the bundles thereof are at rest in said passageway, and means to successively position 55 open casings in alignment with said passageway to receive bundles of articles ejected from the latter by said secondary plunger.
17. A machine of the kind described and as defined in claim 16, in which the means to supply and insert separator elements between the layers of articles forming each bundle thereof comprises, means to provide transverse ways respectively communicating with the sides of said passageway, plungers to reciprocate in said ways, and magazines above said plungers to supply said separator elements thereto.
- In testimony, that we claim the invention set forth above we have hereunto set our 70 hands this 29th day of October, 1927.
- HARRY L. EVANS.
GEORGE I. HOHL.
